HAND TOOL

Albin R. Erickson, Los Angeles, Calif.

Application December 21, 1937, Serial No. 180,960

2 Claims. (Cl. 306—32)

My invention relates to hand tools and has particular reference to a handle for hammers, hatchets, axes or similar hand implements. In hand tool constructions considerable difficulty is encountered in maintaining the head of a tool, such as a hammer, securely upon its handle, the common practice being to employ a head having a tapered eye therein into which a wood handle is inserted and into which handle wedges are driven to expand the material of the handle within the eye of the head. After a relatively short period of use the wedges become loosened and allow the handle to contract within the eye, making the head loose upon the handle.

It is therefore an object of my invention to provide a hammer or similar tool with a handle which may be rigidly secured thereto without the employment of wedges or other expanding devices.

Another object of my invention is to provide a tool of the character described wherein a metal plate is employed having a width at each of its ends greater than the transverse dimensions of the eye of the tool head whereby once the tool head is placed upon the plate it is prevented from accidental removal therefrom.

Another object of my invention is to provide a tool of the character described wherein a metal plate having a width at each of its ends in excess of the transverse dimensions of the eye of the tool head, requiring insertion of the plate into the eye along the diagonals of the eye whereby disposing the plate in parallel relation with either of the transverse dimensions of the eye will prevent accidental removal of the head from the plate.

Another object of my invention is to provide a device of the character set forth in the preceding paragraphs wherein a handle member having a longitudinal head formed therein is adapted to receive the portion of the plate protruding from the eye of the head and adapted to fill the space within the eye upon opposite sides of the plate to prevent turning of the plate relative to the eye.

Another object of my invention is to provide a tool of the character described wherein the eye of the tool head is formed without taper toward its outer end, permitting the insertion of a handle member to fill the eye without expansion, and a plate insertable through the eye along the diagonal of the eye whereby turning the plate after insertion to parallel relation with either of the transverse axes of the eye will prevent accidental removal of the handle from the non-tapered eye.

Another object of my invention is to provide a tool of the character described wherein tapered slots are formed in opposed walls of a non-tapered eye in the tool head and into which eye the plate may be inserted along one of the diagonals of the eye, turned therein and seated in the tapered slot to prevent accidental removal of the tool head from the plate.

Other objects and advantages of my invention will be apparent from a study of the following specification, read in connection with the accompanying drawing, wherein,

Fig. 1 is a perspective view of a hammer equipped with a handle and securing means constructed in accordance with my invention;

Fig. 2 is a longitudinal sectional view taken through the tool head and illustrating the manner in which the securing plate may be inserted therein;

Fig. 3 is an end elevational view corresponding to Fig. 2 and illustrating the manner in which the plate may be inserted in the tool head and turned to be disposed in parallel relation with one of the transverse axes of the eye of the head; and

Fig. 4 is a longitudinal sectional view similar to Fig. 2 and illustrating the plate rotated into parallel relation with the transverse axis of the tool head.

Referring to the drawing, I have illustrated my invention as applied to a hammer, the head of which may be constructed in the usual manner providing a hammer face 2 and claws 3 disposed upon opposite sides of an eye 4. The eye 4 extends through the head 1 and through a shank 5 to receive therein a wood handle 6.

The usual construction of the eye of hammers or similar tools is to taper the eye inwardly from both ends, particularly from the front end 7 of the head so that the handle 6 having a reduced forward end may be inserted into the eye from the rear of the shank 5 and then may be expanded by means of wedges or similar devices to fill the enlarged outer or front end 7 of the eye.

In accordance with my invention, however, the eye 4 is preferably constructed as a rectangular opening, the opposed side walls of which taper only from the rear end so that a reduced end of the wood handle 6 may be driven from the rear of the eye to fill the entire space within the eye without requiring expansion at its outer end.

To hold the handle 6 in secured fixed relation within the eye 4, I provide a securing plate 8

which preferably comprises an elongated relatively thin plate having a width between its ends approximately between the broken lines enclosed within the bracket 9 of less dimension than the longer transverse axis of the eye 4 but having a width at each of its ends as indicated at 10 and 11 greater than the longer transverse axis of the eye 4.

The end 10 is preferably tapered inwardly and rearwardly and is constructed of such dimension as will permit it to pass through the eye 4 from the rear end of the shank 5 when tipped or tilted into parallel relation with one of the diagonals of the eye 4, as is indicated particularly in Figs. 2 and 3. Thus by tipping the plate 10 to the position shown in Figs. 2 and 3, it may be readily inserted from the rear of the shank into and through the eye 4 to the position shown in Fig. 4, at which time the reduced width 9 is disposed within the eye 4, permitting the plate 10 to be rotated about its longitudinal axis to dispose the plate centrally between the side walls 12 and 13 of the eye and in a plane parallel to the surfaces of the walls 12 and 13, as is illustrated in dotted lines 14 in Fig. 3. Then drawing or driving the plate 8 rearwardly to the position shown in Fig. 1 or in dotted lines in Fig. 4, the tapered end 10 of the plate will be driven into tight relation within the eye 4.

The wood handle 6 is provided with an elongated longitudinal slot 6a extending from its forward end adapted to fit the thickness of the securing plate 8 and of a length sufficient to enclose the plate 8. Thus after the plate 8 has been located within the head in the position shown in dotted lines in Fig. 4, the handle 6 may be slipped over the protruding end 11 of the plate and have its reduced end driven into the eye 4 of the head. By reason of the non-tapered construction of the eye 4, the handle end will completely fill the space within the eye as indicated at 6b, preventing rotation of the securing plate 8 toward a diagonal position therein and thus holding the plate securely in place within the eye.

A plurality of screws, bolts, rivets or other securing devices 15 may extend through the two leaves 6c of the handle 6 on opposite sides of the slot 6a and through suitable openings 16 in the plate 8 to secure the plate against forward movement relative to the handle 6.

The plate 8 is preferably constructed of relatively hard material and if desired may be of such character that when driven into its position as shown in dotted lines in Fig. 4 the tapered end of the plate will tend to cut into the material of the head 1 and thus seat itself securely within the head. However, I prefer to provide tapered slots 17 and 18 in the upper and lower walls of the eye 4 as indicated particularly in Fig. 2, the taper of the slots or grooves conforming with the taper of the end 10 of the plate and forming a pre-formed seat for the tapered end of the plate 8. Also if desired shallow grooves 19 and 20 may be provided at diagonally opposite corners of the eye 4 to enlarge this diagonal to permit the more ready insertion of the plate 2.

It will be noted that the rearward portion of the wood handles for tools of this character are

usually larger in cross sectional dimension than the eye of the tool head so that by employing my construction of securing plate 8, insertable from the rear of the shank 5, the rearward end 11 of the plate may be shaped to conform with the surface configuration of this larger portion of the wood handle 6. Thus when the wood handle is in place as shown in Fig. 1, the plate 8 will completely fill the slot 6a, the edges of the plate lying flush with the surface of the wood handle 6 and leaving no depressions or cavities which would otherwise interfere with the comfortable handling of the tool.

It will therefore be observed that I have provided a hand tool in which a wood handle may be secured to the tool head without the employment of expansion wedges or other similar expanding devices and in which the securing plate when assembled with the handle provides a smooth unbroken gripping surface upon the wood 20

handle 6. However, if desired, my handle and securing plate may be employed with the usual construction of hammer or similar tool heads provided with an eye flaring or tapering at opposite ends 25 by merely employing narrow wedges inserted through the front of the eye into the projecting wings of the handle.

While I have shown and described the preferred embodiment of my invention, I do not 30 desire to be limited to any of the details of construction shown or described herein, except as defined in the appended claims.

I claim:

1. In a hand tool, a tool head having an eye 35 formed therein, a handle member insertable in said eye, means for securing said handle member to said tool head comprising a securing plate having one of its ends of greater width than the longer axis of said eye to conform with the width 40 of the handle member and having a width at its opposite end substantially equal to one of the transverse diagonals of the eye and with a reduced width between said ends whereby said plate may be inserted in said eye from the rear thereof along said diagonal and may be turned to parallel 45 the longer transverse axis of said eye, and means for securing said plate to said handle member.

2. In a hand tool, a tool head having an eye formed therein, a handle member insertable in 50 said eye, means for securing said handle member to said tool head comprising a securing plate having one of its ends of greater width than the longer axis of said eye to conform with the width 55 of the handle member and having a width at its opposite end substantially equal to one of the transverse diagonals of the eye and with a reduced width between said ends whereby said plate may be inserted in said eye from the rear thereof along said diagonal and may be turned to 60 parallel the longer transverse axis of said eye, a longitudinal slot formed in said handle member for the reception therein of said securing plate whereby the forward end of said handle member may be disposed within said eye to lock said plate in its position disposed parallel to the said 65 axis of said eye.

ALBIN R. ERICKSON.
